UNITED STATES PATENT OFFICE

BERNARD H. DAVIS, OF FULLERTON, CALIFORNIA

BRIDGING BLOCK FOR WELLS

Application filed November 28, 1932. Serial No. 644,734.

This invention relates to a well drilling apparatus and more particularly has reference to an improved bridging block for wells and to means for positioning and locking same in 5 position.

In performing the usual cementing off process in wells, bridging blocks have previously been provided for bridging the casing at the proper point so that cement may be 10 poured in on top of the block. These blocks have been provided with various means for locking them in place so as to prevent upward or downward movement of the block after it has been set.

One object of this invention is to provide 15 an improved means for lowering a bridging block into a well.

Another object is to provide an improved 20 means for firmly and securely locking a bridging block against downward movement after it has been properly positioned in a well.

Another object is to provide an improved 25 means for expanding a bridging block after it is properly positioned in a well casing.

Other objects and advantages will become 30 apparent from the following description taken in connection with the accompanying drawing. It is to be distinctly understood, however, that the form shown and described is by way of illustration only for the purpose of insuring a complete understanding of this invention, and is not to be taken as in 35 any way being a limitation upon its scope.

The scope of this invention is to be limited 40 only by the prior art and by the terms of the appended claims.

Referring now to the accompanying drawing, in which like numerals indicate corresponding parts throughout:

Figure 1 is a view, partly in longitudinal section, showing the improved bridging block in contracted position inside a well casing.

Figure 2 is a similar view showing the block expanded and locked in position.

Figure 3 is an elevation showing the block alone in expanded position.

Figure 4 is a section taken along the line 50 4-4 of Figure 3.

Figure 5 is a section taken along the line 5-5 of Figure 3, and

Figure 6 is a section taken along the line 6-6 of Figure 3.

Referring now more specifically to the drawing this invention is illustrated as comprising two sections 1 and 2 movably connected at their upper ends by means of a flexible, waterproof element 3 which in the present instance is in the form of a disc of rubberized fabric. The adjacent sides of the sections 1 and 2 are constructed to provide a wedge shaped opening 4 in which a wedge 5 is adapted to operate to spread or expand the sections 1 and 2 from each other. The sections 1 and 2 and the wedge 5 are preferably made of wood or like material.

As shown, the wedge 5 is provided with a pair of openings 6 longitudinally thereof, in which are disposed tension coil springs 7 secured at their lower ends to rods 8 which are in turn secured to the bottom or base of the wedge by screws or other suitable means 9. The upper ends of the spring extend from the wedge and are secured at their upper ends to the flexible member 3 by means such as brackets 10. When not otherwise prevented, the springs 7 will urge the wedge 5 into the opening 4 between the sections so as to expand the sections from each other.

The flexible member 3 is provided with openings 39 registering with the openings 6 through the wedge, and flaps 40 are secured as at 41 to form flap valves closing these openings. By virtue of these valves, water and other liquids in the well may pass by the bridging block while it is being forced down into position, after which the valves will close and retain the cement when it is poured in.

The wedge 5 also has a third opening extending substantially through its center to a point adjacent its lower end or base. This opening has a portion 11 of comparatively large cross section adjacent its lower end, an intermediate portion 12 of considerably smaller diameter, and an upper portion 13 of a diameter larger than that of the portion 12 and smaller than the portion 11. The wedge also has one of its faces cut away

- as at 14 to form a rectangular countersunk portion at a position opposite the lower portion 11 of the opening through the wedge. The relative sizes of the opening 11 and the 5 countersunk portion 14 are such that they are in communication with each other. A metal plate 15 having an opening therein corresponding to the opening 11 is secured to the bottom of the countersunk portion, 10 and pivoted adjacent the opposite upper corners of this plate as at 16 and 17 are a pair of dogs 18 and 19 having teeth 20 projecting from their free ends and longitudinal slots 21 formed intermediate their ends. 15 These dogs extend diagonally across the rectangular countersunk portion as shown so that their slotted portions will overlie the opening 11.
- A rod 22 carrying the bracket 23 at its 20 lower end extends upward from the opening 11 through the small opening 12 into the opening 13. The bracket 23 carries a pivot 24 extending through the slots 21, whereby an upward or downward motion of the rod 22 will cause the dogs 18 and 19 to swing about their pivots 16 and 17 and cause their ends carrying the teeth 20 to project outward beyond the sides of the wedge or to be drawn back within the opening 14. The upper end of the rod 22 is provided with a nut 25 or other head forming member, beneath which is disposed a compression coil spring 26 for the purpose of continuously urging the rod 22 to its uppermost position. 30
- When the bridging block is being placed inside of a well casing 27, the rod 22 is held down against the action of the spring 26 by a mandril 28 which forms a part of the positioning mechanism and extends through a 35 central opening 29 in the flexible member 3 and into the opening 13 in the wedge. This holding down of the rod 22 of course holds the dogs 18 and 19 down with the teeth 20 withdrawn into the countersunk portion 14 out of engagement with the wall of the casing 27. At the same time, the lower end of the rod 22 is pressed against the bottom of the opening 11 to force the wedge 5 downwardly so as to allow the sections 1 and 2 to 45 come closer together.
- On the upper ends of the sections 1 and 2 there are provided cross bars 30 so positioned as to receive the bell shaped disc 31 which is mounted on and fixed to the mandril 28 at such position that it will come in contact with the cross bars 30 when the mandril is far enough to retract the dogs 18 and 19 and shove the wedge 5 down a predetermined amount. 55
- Preferably, for the purpose of forcibly bringing the wedge 5 up between the sections 1 and 2 after the bridging block has been properly positioned, a pair of fine wires 32 are secured to the respective sides of the wedge by means such as the screws 33. They 60

are then passed upwardly and through holes 34 in the disc 31, after which they are wound around the mandril 28 as at 35.

At the upper end of the mandril 28 there is shown a threaded bushing 36 for the purpose of engaging the threaded interior of the tubing 37. A nut 38 or other suitable means is provided at the upper end of the mandril 28 to hold the mandril 28 in place in the bushing 36.

It will be apparent from the above description that the bridging block is pushed or driven into position in the casing 27 by means of the tubing 37, the mandril 28 and the disc 31. The tubing 37 is forced downwardly causing the mandril to push the rod 22 down against the compression of the spring 26 thus retracting the toothed ends of the dogs 18 and 19 and at the same time forcing the wedge 5 downwardly with respect to the sections 1 and 2 allowing them to draw closer together. At the same time, the disc 31 is forced against the cross bars 30 to cause the sections 1 and 2 to move downwardly until their proper position is reached.

When this position is reached, the tubing, bushing, mandril and disc are then drawn up allowing the spring 26 to raise the rod 22 and expand the dogs 18 and 19 so as to engage the teeth 20 with the walls of the casing 27. At the same time, with the rod 22 lifted from the bottom of the opening 11 in the wedge, the springs 7 are allowed to draw the wedge up between the sections 1 and 2 to expand them from each other and cause them to engage the walls of the casing 27. In order to more firmly seat the wedge between the sections 1 and 2, continued upward movement of the tubing 37 and the parts attached thereto will draw the wires 32 tight and they will draw the wedge up so that it will seat more firmly. The dogs 18 and 19 will prevent the wedge from moving downwardly again. Further upward movement will break the wires, after which the positioning assembly may be withdrawn from the well to permit the pouring of cement on top of the bridging block as hereinbefore set forth.

As will readily appear from the above description, a means has been described for carrying out all of the objects of this invention and for more advantageously bridging a well so that the cementing off process may be carried out.

What I claim is:—

1. In a bridging block for wells, a body comprising two sections movable to occupy expanded and contracted positions, a wedge between the sections with its apex disposed upwardly to force said sections to expanded position and lock them within a well casing, means on the wedge to normally engage the walls of the well casing and prevent downward movement of the wedge with respect to the casing, and means to hold said first men- 125

- tioned means out of engagement with the walls of the casing during the positioning of the bridging block.
2. In a bridging block for wells, a body comprising two sections movable to occupy expanded and contracted positions, a wedge between the sections with its apex disposed upwardly to force said sections to expanded position and lock them within a well casing, a locking dog on the wedge to normally engage the wall of the well casing and prevent downward movement of the wedge with respect to the casing, and means to hold said dog out of engagement with the wall of the casing during the positioning of the bridging block.
3. In a bridging block for wells, a body comprising two sections movable to occupy expanded and contracted positions, a wedge between the sections with its apex disposed upwardly to force said sections to expanded position and lock them within a well casing, means between the wedge and the sections to normally force the wedge upward to expand the sections, means on the wedge to normally engage the walls of the well casing and prevent downward movement of the wedge with respect to the casing, and means to hold the wedge in its downward position with respect to said two sections, and simultaneously to hold said second mentioned means out of engagement with the walls of the casing during the positioning of the bridging block within the well casing.
4. In a bridging block for wells, a body comprising two sections movable to occupy expanded and contracted positions, a wedge between the sections with its apex disposed upwardly to force said sections to expanded position and lock them within a well casing, means between said wedge and said two sections to normally force the wedge upwardly between the sections to expand them against the well casing, means to hold said wedge in a downward position with respect to said two sections while positioning the bridging block within a casing, and a disc on said last mentioned means for engaging said two sections to force them into position within the casing.
5. In a bridging block for wells, a body comprising two sections movable to occupy expanded and contracted positions, a wedge between the sections with its apex disposed upwardly to force said sections to expanded position and lock them within a well casing, means between the wedge and said two sections to normally force said wedge between said sections to expand them against the walls of the well casing, a rod extending between said sections and engaging said wedge to force the same downwardly and allow said two sections to move to contracted position during the positioning of the bridging block within the well, and a disc member mounted on said rod above said sections and adapted to engage said sections when said wedge is moved to its downward position, whereby said bridging block may be forced into position within the well casing.
6. In a bridging block for wells, a body comprising two sections movable to occupy expanded and contracted positions, a wedge between the sections with its apex disposed upwardly to force said sections to expanded position and lock them within a well casing, means between said wedge and said two sections to normally force said wedge upwardly between said sections to expand the same, and a positioning means for said bridging block comprising a mandril extending between said two sections and forcing said wedge downwardly to allow the sections to move to contracted position, a positioning disc member mounted on said mandril above said sections to engage said sections when said wedge is moved downwardly to allow said sections to move to their contracted positions, and a threaded bushing mounted on said mandril above said disc member and adapted to be threadedly engaged by a section of tubing for the purpose of operating said positioning means.
7. In a bridging block for wells, a body comprising two sections movable to occupy expanded and contracted positions, a wedge between the sections with its apex disposed upwardly to force said sections to expanded position and lock them within a well casing, means to force said wedge downwardly and allow said sections to move to contracted position during the positioning of the bridging block within the well, means for positioning the bridging block within the well, and a pair of frangible members secured to said positioning member and to opposite sides of said wedge member, whereby said wedge member may be pulled upwardly and into position between said two sections and firmly set therebetween by a short upward movement of the positioning means, and said positioning means afterward withdrawn from the well by fracturing said frangible members.
- In testimony whereof, I affix my signature hereto.
- BERNARD H. DAVIS.
